(57) **CLAIM**

The ornamental design for an electronic display device, as shown and described.

DESCRIPTION

FIG. 1 is a top, front, left perspective view of an electronic display device.

FIG. 2 is bottom, rear, left perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side view thereof.

The broken lines depict portions of the electronic display device which form no part of the claimed design.
